(57) **CLAIM**

The ornamental design for a mitre saw fence scale, as shown and described.

DESCRIPTION

FIG. 1 is an isometric view of a mitre saw fence scale, shown in use; and,

FIG. 2 is a front view thereof.

The broken lines in the drawings depict unclaimed environmental subject matter.

The cutaway symbols illustrated in break lines in the drawings indicate a symbolic break in the design for the mitre saw fence scale. The appearance of any portion of the article between the break lines forms no part of the claimed design.
